UNITED STATES PATENT OFFICE.

THEODOR J. BUERGER, OF MINNEAPOLIS, MINNESOTA, ASSIGNOR OF ONE-FOURTH TO
JOSEPH J. BUERGER, OF MINNEAPOLIS, MINNESOTA.

COLLAR-SPACER.

1,137,571.

Specification of Letters Patent. Patented Apr. 27, 1915.

Application filed August 31, 1914. Serial No. 859,365.

To all whom it may concern:

Be it known that I, THEODOR J. BUERGER, a citizen of the United States, residing at Minneapolis, in the county of Hennepin and State of Minnesota, have invented certain new and useful Improvements in Collar-Spacers, of which the following is a specification.

My invention relates to collar spacers and 10 has for its object to provide a device by means of which the adjacent portions of a turned-down collar may be crimped either immediately after laundrying or at any subsequent time, so that the portions of said 15 collar will be spaced apart and the tie can be slid within this space.

The full objects and advantages of my invention will appear in connection with the detailed description thereof and are particularly pointed out in the claims.

In the drawings, illustrating the application of my invention in one form,—Figure 1 is an end view of one of my spacers. Fig. 2 is a sectional view similar to Fig. 1 showing the manner of using the spacer. Fig. 3 is a sectional end view taken on line 3—3 of Fig. 2. Fig. 4 is a plan view of the device. Fig. 5 is a sectional view through the collar showing the manner in which the 20 mechanism serves to space the portions of the collar.

As shown, two strips of spring metal 10 and 11 are fastened together, as indicated at 25 12, the portions 10 and 11 being normally sprung outwardly, while rear portions 13 and 14 may be slightly arched and brought to a point at 15 for insertion between the 30 portions of the collar. The arm 10 is provided with a box-like enlargement 16, and 35 the arm 11 with a similar box-like enlargement 17. In enlargement 16 is mounted a transverse pin 18, a similar transverse pin 19 being mounted in enlargement 17. Upon 40 pin 18 is journaled a roller 20 and another roller 21 of less diameter than roller 20. Upon pin 19 is journaled a roller 22 opposite roller 21 of the same diameter as roller 20, and a roller 23 opposite roller 20 of the 45 same diameter as roller 21. It will thus be seen that when these rollers are brought into 50 proximity they will, respectively, overlap and engage, roller 22 engaging roller 21 and overlapping roller 20, which engages roller 23. If, now, inner flap 24 of the collar is 55 placed between the sets of rollers and pres-

sure applied, as indicated in Fig. 2, a right-angled crease 25 may be produced by running the rollers around the collar, said rollers being guided by an edge 26 of the collar engaging the curved bottom 27 formed by 60 the junction of the arms 10 and 11. When this crease has been completed it will, as shown in Fig. 5, offset the outer flap 28 from the inner flap 24, leaving a slide space 29 for the band of the tie. This removes 65 the frictional contact of the two flaps of the collar from the tie-band and permits the same to be slid between the flaps in tying and adjusting the knot or bow of the tie.

It will be obvious that my device is simple 70 in construction and will prove efficient for the purpose. If desired, ears 30 may be formed upon the tops of the box-like portions 16 and 17 to give a stronger grip to the thumb and finger in forcing the rollers 75 upon the flap of the collar and moving said rollers along said flap to make the crease. As above stated, this device can be used by the laundryman to put the crease in the collar immediately after laundrying; but its 80 highest efficiency will be at the home, where the crease can be made immediately before fastening on the collar and when the tie space 29 will be most effectively provided. Each of the respective pairs of rollers upon 85 transverse pins 18 and 19 may be made of one piece, preferably of wood. It is also to be noted that the pointed end 15 of the device may be advantageously employed to open the buttonholes of the collar prior to 90 its being secured upon the collar button.

I claim:

1. A spacer for turned-down collars comprising a pair of arms normally held apart, means on said arms for engaging the flap of 95 the collar and forming a crease therein, and a guide for engaging the edge of the flap to cause the crease to be made parallel with said edge.

2. A spacer for turned-down collars comprising a pair of arms normally held apart, means on said arms for engaging the flap of the collar and forming a crease therein, and a guide for engaging the edge of the flap to cause the crease to be made parallel 105 with said edge, said guide comprising a curved seat formed by the junction of said arms.

3. A spacer for turned-down collars comprising a pair of normally separated arms 110

of spring material, and a pair of rollers of different diameters journaled upon each arm, the smaller roller on one arm being engageable with the larger roller on the other arm, so that when said rollers are forced upon a flap of the collar inserted between the same and drawn along said flap the rollers will form a right-angled bend in the flap which causes said bent flap to be spaced from the other flap when the collar is in position upon the wearer.

4. A spacer for turned-down collars comprising a pair of normally separated arms of spring material, a box-like projection formed at the end of each of said arms and opening toward each other, a pin across each of said openings, and a pair of rollers of different diameters journaled upon each pin, the smaller roller on one arm being engageable with the larger roller on the other arm, so that when said rollers are forced upon a flap of the collar inserted between the same and drawn along said flap the rollers will form a right-angled bend in the flap which causes said bent flap to be spaced from the other flap when the collar is in position upon the wearer, and flanges on the outside of said box-like members, said members and flanges providing means for gripping the same between the thumb and finger to apply pressure to the rollers and flap of the collar between the same.

In testimony whereof I affix my signature in presence of two witnesses.

THEODOR J. BUERGER.
